Primary Examiner — Ricky Pham(74) *Attorney, Agent, or Firm* — Carter, Deluca & Farrell LLP(57) **CLAIM**

The ornamental design for a stove cover, as shown and described.

DESCRIPTION

FIG. 1 is a perspective view of a stove cover in accordance with the present design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines shown in the drawings illustrate portions of the stove cover that form no part of the claimed design.
